PUMP

Filed Oct. 2, 1924

Fig. 1.

Patented Oct. 25, 1927.

UNITED STATES PATENT OFFICE.

WILLIAM H. FURNESS, OF NATIONAL PARK, NEW JERSEY, ASSIGNOR TO CELLOCILK COMPANY, OF PHILADELPHIA, PENNSYLVANIA, A CORPORATION OF DELAWARE.

PUMP.

Application filed October 2, 1924. Serial No. 741,134.

The invention relates to a fluid pump and has for its primary objects the provision of a pump which is small in size, quiet in operation, exceedingly simple in construction, and free from excessive vibrations.

Another object of my invention is the provision of a pump which may be made ineffective without stopping the driving device and without the use of valves or other fluid 10 cut-off means.

Still another object of my invention is the provision of a pump in which the pressure and quantity of output may be varied without changing the speed of the driving 15 mechanism and without the use of reducing valves.

Still another object of my invention is the provision of a pump which when made ineffective will change the position of the 20 discharge outlet or nozzle.

Still another object is the provision of a pump in which leakage is automatically prevented by the pressure within the pump.

A pump having the above characteristics 25 among other uses is particularly useful in the manufacture of artificial silk thread.

How the foregoing together with such other objects and advantages as may hereinafter appear, or are incident to my invention, are obtained is illustrated in the accompanying drawings in preferred form 30 wherein

Fig. 1 is a partial elevation and section of my pump taken substantially on the line 35 1-1 of Fig. 3.

Fig. 2 is a plan view of Fig. 1 with the cover plate removed.

Fig. 3 is an end elevation looking toward the right in Fig. 1, with some of the parts 40 broken away and showing a tank containing a bath.

Fig. 4 is an inverted view of the cover plate.

Referring to the drawings the reference 45 character A denotes the pump base which carries the pump body B, and the drive shaft C having worm drive connection to the pressure creating means as indicated at D and a pulley E for connection to the source 50 of power which connection, however, may be made direct to the shaft C.

The pressure creating means is composed of an internal gear 7 mounted for rotation in the body B, a rotatable external gear or 55 pinion 8 mounted to mesh with the internal

gear, and a member 9 pivoted at 10 in the crescent like space between the non-meshing portions of the gear. The pinion 8 is slidably splined to the shaft 11 by means of a key 12, which shaft is rotated by the worm 60 wheel 13 of the worm drive D. The portion 11^a of the shaft is slightly rounded so that the machining of the gear and body need not be extremely accurate. The gear is thus prevented from cutting into the body which 65 would be the case if it were securely fastened to the shaft. Thus it will be seen that rotative movement of the pinion 8 in the direction of the arrow is imparted in the same direction to the internal gear 7. 70

The crescent-like space above referred to is divided into an intake chamber *a* and a pressure chamber *b* by the member 9, said chambers having a height equal to the width of the internal gear and pinion, the lower 75 wall being formed by the portion 14 of the body B and the upper wall being formed by the disc-like cover plate 15. This cover plate 15 is held in place by means of the nut 16 and serves to hold the gears against 80 displacement. A fluid inlet opening is provided at 17 in the inlet chamber and a pressure discharge outlet 18 is provided in the cover plate said outlet communicating with the pressure chamber *b* by means of a passage 19 in the cover plate located adjacent the end of the length of tooth contact at the pressure chamber side in which area 85 pressure conditions are best.

The advantages realized by the use of internal gears as a pressure creating means are manifold. Among others are the great length of tooth contact which reduces the leakage from the pressure to the intake chamber to a minimum and makes for long 90 life and quiet running of the gears; the close centre distance of the gears enabling the use of large gears without making the pump excessive in size and the peculiar way in which the space between gears may be 100 divided into an inlet and pressure chamber.

In operation, the pump as thus far described, takes in fluid at 17, passes fluid from the intake chamber to the pressure chamber by means of the pockets formed between 105 teeth of the gears by virtue of the member 9 engaging the tops of such teeth, and discharges the fluid thru the outlet 18 at a pressure determined by the speed of the pump, the size of the outlet and the amount of leak- 110

age past the meshing teeth of the gears. A gauge 18^a is provided above the discharge outlet for indicating the pressure condition within the pump. As a means for varying the pressure output of the pump, in a simple and novel manner, I have mounted the pinion shaft 11 in a bearing 20 having an eccentric bore and carried by the sleeve-like extension 20' of the pump body. By virtue of this I am enabled to change the relation of the gears, that is to say they may be positioned in tight or loose mesh, within the range of effective driving mesh of the gears. As a means for adjusting the eccentric bearing I have shown a handle 21 screw threaded into the eccentric bearing and passing through an elongated slot 21' in the extension 20' of the body, which slot serves to limit the amount of adjustment. Thus by varying the relation of the gears the pressure output of the pump may be varied. By screwing the handle up tight the shaft may be locked in adjusted position, but adjustment is made by swinging the handle 21 to one side or the other of the elongated slot 21'.

In this connection it is pointed out that the pivoted member 9 is split at its free end as clearly shown in Fig. 2, thus making the member resilient to allow the aforesaid change in relation of the pump gears. Furthermore, it will be seen that by so constructing the member 9, proper contact is maintained between it and the teeth of the pump gears, the member serving as a means in itself compensating for wear of the contacting surfaces.

Leakage past the shaft and eccentric bushing is automatically prevented by the pressure within the pump, such pressure bearing down on the shaft by reason of the passage 19 extending across the upper surface of the shaft and causing the enlarged portion 22 of the shaft to make a seal at the seat 22^a in the eccentric bushing which in turn causes the enlarged portion 23 of the bearing 20 to close tightly on its seat 20^a.

The pump body B is mounted in the base for swinging movement to which end it is pivoted at 24 by means of pivot pins 25 and 26. The pins 25 and 26 are provided with head portions 27 having upwardly extending lugs adapted to be riveted to the body B, the heads of the pins serving to hold the body against displacement. In this instance fluid is introduced to the inlet chamber through a passage 28 extending through the pin 26, suitable swinging connection being made at 29 to the supply pipe.

The pivotal mounting of the pump body just described is for the purpose of throwing the worm wheel 13 into and out of mesh with the worm of the worm drive C. This may be accomplished by manipulating the screw 30 which engages the shank or exten-

sion 20' of the body below the pivot. It will be seen that by turning the screw outward the body may be swung until the worm wheel becomes disengaged from its worm, which causes the worm to run idle and the pump to stop. In order to avoid jamming the worm wheel when engagement is made I provide an adjustable stop in the form of a set screw 31 which limits the inward movement of the pump body.

When desired I may provide the pressure discharge pipe with a nozzle 32 and immerse it in a bath contained in a suitably positioned tank. The relation of the discharge pipe to the tank is such that when the pump body is swung to disengage the drive it will at the same time withdraw the discharge pipe from the tank. Such an arrangement is particularly desirable when the pump is used for spinning filaments to be subsequently twisted into a thread, which is the procedure followed in making artificial silk thread. When so used the fluid supplied to the pump is of a substance which will gel when forced through restricted openings under pressure into a treating bath.

By actual test it has been found that very high pressures may be obtained from a pump of relatively small size in comparison with other gear pumps now in use.

While my invention has been described for use as a pump it is obvious by reversing its operation it may be used as a meter, that is to say fluid may be passed through under pressure and measured by the speed of the gears.

I claim:

1. A pump including a pump body, fluid pressure creating means carried in said body comprising, an internal gear and pinion and means for altering the relation of said gear and pinion whereby pressure and capacity conditions may be varied.

2. A pump of the character described comprising in combination a casing, an internal gear and pinion, a shaft for said pinion, an eccentric bearing for the shaft, and means for shifting the bearing for altering the pressure output of the pump.

3. A pump comprising in combination, an internal gear and pinion, means for varying the meshing relations between gear and pinion, a resilient member dividing the space between the gear and pinion, an inlet to one space, an outlet from the other space, and means for driving the gear and pinion.

4. A pump comprising in combination, an internal gear and pinion, a resilient member dividing the space between the gear and pinion, an inlet to one space, an outlet from the other space, and means for driving the gear and pinion.

5. A pump, comprising a casing, pressure creating means composed of an internal gear

and pinion, means for altering the relation of said gear and pinion, a resilient member dividing the crescent like space between the non-meshing portions of the gears into a fluid intake chamber and a pressure chamber, and functioning to form means whereby fluid may be passed from one chamber to the other.

6. A pump comprising in combination, 10 pump gears, a drive shaft for one of said gears having an enlarged portion, a bearing for the drive shaft having a seat portion, said enlarged portion being pressure held to said seat portion to form a seal between 15 the shaft and bearing.

7. A pump comprising in combination, pump gears, a drive shaft for one of said gears having an enlarged portion, a bearing for the drive shaft having a seat portion, 20 said enlarged portion being held to the seat portion by the pressure discharge of the pump.

8. A pump comprising a casing, an internal gear and pinion, a member dividing 25 the crescent like space between the gear and pinion into two chambers, a fluid inlet for one chamber, a pressure discharge outlet, a passage between the other chamber and the outlet, a shaft for the pinion having an end 30 subject to the pressure within said passage, and means in association with the shaft for maintaining a seal against leakage of fluid past the shaft, said means being made effective by the pressure on the shaft.

35 9. A pump of the character described comprising in combination a casing, an internal gear and pinion, a shaft for said pinion, a bearing for said shaft carried by the casing, means whereby a tight seal against leakage 40 of fluid is maintained between the pinion shaft and bearing, and means whereby a

tight seal against leakage of fluid is maintained between said bearing and said pump casing.

10. A fluid pump comprising, a base member, 45 driving means carried thereby, a pump body pivoted to the base member, pressure creating means in said body adapted to be connected to and disconnected from the drive means by swinging the body on its pivot. 50

11. A fluid pump comprising, a base member, driving means carried thereby, a pump body pivoted to the base member, pressure creating means in said body adapted to be connected to and disconnected from the 55 drive means by swinging the body on its pivot, together with means for introducing the fluid to the pressure creating means thru the pivot.

12. A pump comprising in combination, 60 pump gears, a drive shaft for one of said gears, means whereby a flexible connection is made between said shaft and gears, and an enlarged portion on said shaft held to its seat by the pressure discharge of the pump. 65

13. A pump comprising in combination, an internal gear and pinion, self compensating means dividing the space between the gear and pinion, an inlet to one space, an outlet from the other space, and means for 70 driving the gear and pinion.

14. A pump including a pump body, an internal gear and pinion carried in said body, self compensating means dividing the crescent-shaped space between the gear and 75 pinion into two chambers, a fluid inlet for one chamber and a pressure discharge outlet for the other chamber.

In testimony whereof, I have hereunto signed my name.

WILLIAM H. FURNESS.
